UNITED STATES PATENT OFFICE.

WILLIAM DOYLE, OF BALBOA, CANAL ZONE.

BUILDING CONSTRUCTION.

1,144,894.

Specification of Letters Patent. Patented June 29, 1915.

Application filed September 18, 1914. Serial No. 862,407.

To all whom it may concern:

Be it known that I, WILLIAM DOYLE, a citizen of the United States, residing at Balboa, in the Territory of Canal Zone, Republic of Panama, have invented certain new and useful Improvements in Building Construction; and I do hereby declare the following to be a full, clear, and exact description of the invention, such as will enable others skilled in the art to which it appertains to make and use the same.

This invention relates to new and useful improvements in building construction and has for its principal object to provide a novel method of constructing building walls to render the same water and air tight.

Another object of the invention, is to provide a building wall having a dead air space formed therein, which materially assists in maintaining the interior of the building at a constant temperature.

A still further object of the invention is to provide a simplified construction of wall which will render the same fire-proof as well as moisture-proof and which will facilitate and cheapen such construction.

A still further object of the invention is to provide an exterior construction which will permit the user, when so desired, to change the interior of the structure without affecting the exterior in any way.

A further and more specific object of the invention is to provide a building which is particularly adapted for use in tropical climates, wherein it is of utmost importance to keep the inner walls dry and also keep the interior of buildings cool.

Heretofore it has been the practice in putting up buildings of concrete construction to tie the inner and outer walls in some suitable way or to use small blocks. Both of these methods have been found very deficient, since the moisture will pass from the outer wall through the connecting means to the inner wall and thus injure the interior finish. The old type of wall is also disadvantageous for the reason that the inner structure can not be changed nor removed without disturbing the outer wall and due to the fact that it is frequently necessary to get at the space between the walls in order to remove any vermin or other pests of an undesirable nature, it is apparent that these walls are not altogether satisfactory.

With these and other objects in view the invention consists in the combination and

arrangement of parts which will be fully set forth in the following specification and in the accompanying drawing, in which:

Figure 1 is a fragmentary view of a wall constructed in accordance with this invention, the same being partially broken away to clearly illustrate the details of construction. Fig. 2 is a transverse sectional view taken on line 2-2 of Fig. 1. Fig. 3 is a horizontal sectional view of a wall constructed in accordance with this invention and showing the same complete. Fig. 4 is a view similar to Fig. 3 illustrating the wall without the finish coat, and Fig. 5 is a view similar to Fig. 3 illustrating the wall without the backing coat.

Referring now to the drawings by characters of reference, the numeral 1 designates the foundation or sill of a building of the usual construction, to which the usual studs 2 are secured. These studs extend upwardly as clearly shown in the drawings, and are arranged to support the interior structure during the process of construction of the building. Extending upwardly at spaced intervals from the studs 1 are provided the angle bars 4 which are embedded in the foundation and are arranged to form support for the wire fabric 6. These angle bars 4 are stapled, wired or otherwise secured to the roof rafters 3 and after the building has been completed and the settlement thereof started, the angles 4 assist in supporting the superstructure. This wire fabric 6 forms the base to which the stucco mixture, which will be more fully hereinafter described, is applied.

The stucco hereinbefore referred to is preferably of three coats as will be more fully hereinafter described, but it is to be understood that when so desired any number of finishing coats may be applied at the desire of the user. The first coat to be applied to the angles and wire fabric hereinbefore described, is the scratch coat designated by the numeral 7 this, scratch coat 7 is placed in position and keyed as at 8 through the spaces formed by the wire fabric 6. It will thus be seen that the coat will be firmly held in place and is in readiness to receive the finish coat and backing coats, which will be more fully hereinafter described. The backing coat which is designated by the numeral 9 is then put in place and is arranged so that it adheres to the keys 8 of the scratch coat and forms a smooth surface en-

tirely embedding the uprights 4 and wires 6. It will thus be seen that the entire outer structure will be incased in a protective coating which will prevent the same from rusting and from becoming weakened. The finish coat 10 is then applied to the scratch coat, and this finish coat may be given any desired finish which will suit the user.

As soon as the outer structure described in the above paragraph has been completed, the studs 2 are then furred and plastered on their inner sides in the ordinary way thus closing the openings between the studs and forming a dead air space between the outer and inner wall structures which will effectively serve to maintain the temperature in the building constant since a dead air space of this character acts as an insulator against heat and cold. This dead air chamber also prevents the passage of moisture through the wall and since the walls are wholly independent of each other, there is nothing to convey heat, cold nor moisture across the dead air space from the outer to the inner wall structure. It is also noted that the outer wall structure being monolithic will prevent vermin from infesting the building thereby rendering the same vermin proof. Due to the fact that the reinforcing elements of the outer wall structure are wholly incased in the protective coating of concrete, it will be apparent that any deterioration thereof will be eliminated as there is no effect of the elements thereon. In view of the fact that the wall structures are spaced from each other it is possible to use this space for the accommodation of pipes and conduits and thus the floor space of a building constructed in accordance with this invention is materially increased.

After the studs have been set in place and the outer wall structure completed, it is ap-

parent that the concrete of the outer structure immediately begins to set and by the time the interior of the building and superstructure has been completed and settles, it will be apparent that the outer structure will have set sufficiently to sustain any weight which might be placed thereon thereby materially strengthening the building and preventing the cracking or buckling of the outer wall structure before the same has been properly hardened. It will also be evident that this wall structure will be capable of supporting the roof and interior structure thus relieving the studs of much of the strain of supporting a building.

While in the foregoing there has been shown and described the preferred embodiment of this invention, it is to be understood that such changes in the combination and arrangement of parts as may fall within the scope of the claim may be resorted to without departing from the spirit and scope of the invention.

Having thus described the invention, what is claimed as new, is:—

A building of the character described including a foundation, disconnected independent inner and outer wall structures providing an air space carried by said foundation, the inner wall structure being of a relatively temporary and removable character, the outer wall structure being of reinforced monolithic construction and relatively permanent in character, and each wall structure being capable of sustaining the weight of the building independent of the other.

In testimony whereof I affix my signature in presence of two witnesses.

WILLIAM DOYLE.
